UNITED STATES PATENT OFFICE.

HAROLD E. McCREERY, OF APOLLO, PENNSYLVANIA, ASSIGNOR TO APOLLO HOLDING CORPORATION, OF APOLLO, PENNSYLVANIA, A CORPORATION OF DELAWARE.

ROLL HEATER.

Application filed July 27, 1927. Serial No. 208,881.

This invention relates to roll heaters and more particularly to heaters for the rolls employed for rolling sheet metal in sheet mills.

As is well known, sheet metal rolls derive their heat from the hot sheets passed therebetween, but it has been found that the heating action takes place unevenly whereby the rolls are slightly concaved from end to end thus resulting in the rolling of sheets which are slightly thicker in the central portion than at the edge portions.

An important object of the invention is to provide a roll heater which may be used during the operation of the rolls to assist in the proper distribution of heat to the rolls to maintain the true cylindrical shapes thereof and thus provide rolled sheets of uniform thickness.

A further object is to provide a novel heater a plurality of which are adapted to be arranged adjacent the rolls and conform in curvature thereto, novel heating means being provided for effectually heating the rolls without causing the cracking thereof, or other injuries.

A further object is to provide a heater having a chamber which is open at its bottom to receive a novel form of burner, the inner wall of the chamber being arranged in proximity and conforming in curvature to the roll whereby the hot products of combustion passing upwardly through the chamber will transmit heat to the roll.

A further object is to provide a heater of the character referred to which is adapted to be used during the operation of the rolls and which is provided with small rollers adapted to facilitate the handling of the sheets.

A further object is to provide a heater having a chamber in which products of combustion are adapted to flow upwardly, and a stack communicating therewith to permit the products of combustion to flow downwardly and thus maintain a high temperature in the heating chamber and preventing the products of combustion from flaring outwardly into the faces of operators.

A further object is to provide a novel form of burner for the heater.

A further object is to provide novel means for supporting the heater whereby the latter may move away from the rolls if the latter should break, and thus prevent damage to the heater and associated parts.

Other objects and advantages of the invention will become apparent during the course of the following description.

In the drawings I have shown one embodiment of the invention. In this showing,

Figure 1 is a side elevation of the apparatus in operative position adjacent the rolls,

Figure 2 is a horizontal sectional view on line 2—2 of Figure 1, the gas supply means being omitted,

Figure 3 is a fragmentary plan view of a portion of one heating casing and the supporting means therefor,

Figure 4 is a detail section on line 4—4 of Figure 1,

Figure 5 is a side elevation of one of the burners, parts being shown in section, and,

Figure 6 is a detail section on line 6—6 of Figure 5.

Referring to the drawings the numeral 10 designates upper and lower rolls journaled in the usual roll housings 11 and adapted to roll metal sheets 12 fed therebetween. The elements described are of the usual construction and form no part of the present invention.

Referring to Figure 4 the numerals 13, 14, 15 and 16 designate a plurality of heaters which are identical in construction, and hence only one need be referred to in detail. During the normal operation of the rolls it is preferred that only the heaters 13 and 15 be employed, the other heaters 14 and 16 being placed in position when the rolls are not in use to assist in maintaining the proper temperature therein.

Each heater comprises inner and outer walls 17 and 18 divided by a central wall 19 to form a burner chamber 20 and an outlet chamber or stack 21. The chambers 20 and 21 are closed by end walls 22 the upper portions of which project outwardly beyond the casing as at 23 to form bearings for a roller 24. The outer wall 18 terminates above the center wall 19 and is flared outwardly at its lower end as at 25. Each heater further is provided with a plurality of relatively small rollers 26 which are adapted to contact with one of the rolls 10 to properly space the heating casing therefrom. It will be obvious that the inner wall 17 of each burner is curved to conform to the curvature of one of the rolls 10 and is arranged substantially parallel thereto.

A burner indicated as a whole by the

numeral 27 is arranged in the lower portion of each of the chambers 20, as indicated in Figure 4. Referring to Figures 2, 5 and 6, it will be noted that each burner includes 5 concentric inner and outer sleeves 28 and 29 respectively, the inner sleeve being provided in its lower portion with outlet openings 30 while the outer sleeve 29 is provided in its upper portion with similar outlet openings 10 31. A cap 32 is arranged at one end of the sleeve and is provided with a recess 33 in which the adjacent ends of the sleeves are arranged. An inlet cap 34 is arranged adjacent the opposite ends of the sleeves 28 15 and 29 and is provided with an annular recess 35 in which the adjacent ends of the sleeves are received. A bolt 36 extends through the inner sleeve, the ends of the caps, and the end walls 22 of the associated 20 burner casing as shown in Figure 2, this bolt serving as the means for securing the caps 32 and 34 against the burner tubes or sleeves 28 and 29. The cap 34 is provided with a chamber 37 communicating with the space between the sleeves 28 and 29, this chamber also being provided with openings 38 similar to the openings 31 previously described. The cap 34 is provided in one side with an inlet conduit 39 through which gas flows into the 25 sleeve 28.

The end of the conduit 39 is provided with an elbow 40 in which is threaded the inner end of a mixing chamber 41, having openings 42 in which air is adapted to flow. 35 A burner nozzle 43 fits into the outer end of the mixing device and is provided with a jet 44 which is interchangeable according to the fuel being employed. A pipe 45 connects the burner nozzle to a control valve 46 which, in turn, is connected to a pipe 47. The pipe 47 is provided with a relatively 40 small pipe 48 extending therefrom and adapted to act as a pilot for the burner, as will be apparent. A gas supply pipe 49 is 45 connected to the pipe 47.

Means are provided for supporting the heaters in proximity to the rolls and for permitting movement of the heaters away from the rolls if the latter should break, the outward movement of the heaters serving to prevent damage thereto. Referring to Figures 1, 50 3 and 4, the numeral 50 designates a bracket above which is mounted an arm 51. A bolt 52 is threaded in the arm 51 and has a cylindrical lower end slidably received in the opening in the bracket 50. The outer end of the arm 51 is pivotally connected by a bolt 53 to an inner arm 54 which is normally arranged at an angle to the arm 51, as shown 55 in Figure 3. The bolt 53 extends upwardly a substantial distance above the arms 51 and 54 and is surrounded by a coil spring 55, the tension of which may be adjusted by a nut 56. One of the arms 54 and associated elements is provided for each end of 60 65

each of the heaters and the end walls of the latter are provided with ears 57 which rest upon the arms 54. A bolt 58 is threaded in the inner end of each arm 54 and is slidably received in each of the ears 57. 70

The operation of the apparatus is as follows:

Gas is supplied to the inner sleeve 28 from the nozzle 43, through the mixing device 41, elbow 40 and inlet conduit 39. Air 75 is admitted into the mixing device through the openings 42, as will be apparent. It has been found that the mixture of air and gas in the mixing device, which is of the usual construction, is inefficient for making 80 a perfect combustible mixture. Accordingly the sleeves 28 and 29 are provided and it has been found that this structure greatly increases the efficiency of the explosive mixture by more efficiently mixing the air 85 and gas whereby perfect combustion is obtained. The gas and air flow outwardly from the sleeve 28 through the openings 30 therein and circulate around the inner sleeve. The gas flows outwardly from the sleeves 29 through the openings 31 therein, the latter openings providing burner openings at which point the gaseous mixture is ignited. The provision of the openings 38 in the cap 34 serves to provide flames substantially throughout the length of each roll. The flames pass upwardly through the burner chamber 20 and heat the inner wall 17 thereof, heat being transferred to the adjacent roll 10 to maintain the latter at the 90 proper temperature. The products of combustion then flow downwardly through the outer chambers or stacks 21 to the atmosphere, these stacks serving to prevent the products of combustion from flaring up in 100 the faces of operators and also serving to maintain a high temperature in the burner chambers. 105

As previously stated, the heaters 13 and 15 ordinarily are employed while the rolling 110 mill is in operation, while the heaters 14 and 16 are added when operation of the mill is stopped, to retain the rolls at the proper temperature. The rolls normally are heated by the hot sheets passing therebetween so 115 that only two heaters are necessary during the operation of the rolls. As pointed out, it has been found that the rolls become slightly concaved from end to end during their normal operation and the provision of 120 the heaters serves more efficiently to heat the rolls and retain the latter in their true cylindrical shapes. It is the common practice to pass sheets through the rolls and then return the sheets to the inlet side of the rolls whereby they again may pass therebetween. This 125 action usually is accomplished by passing the sheets back over the upper roll 10 after each rolling operation, and the rollers 24 of the heaters 15 and 13 facilitate the removal of 130

the sheets from the rolls 10 and the returning of the sheets to the inlet side of the rolls.

While the rollers 24 of the heaters 14 and 16 ordinarily are not used, it is preferred that the heaters be made identical so that either may be placed in any desired position. The small rollers 26 serve properly to space the heaters from the rolls 10 whereby the inner walls 17 of the heaters may be arranged in close proximity to the rolls without scraping thereagainst. All of the heaters illustrated in Figure 4 are employed when the rolls are not being used, in which case the rolls will be continuously rotated to evenly distribute the heat from the heaters.

The bolt 53 and associated elements provide friction means for connecting each pair of arms 51 and 54. The friction between the parts may be adjusted by varying the tension of the springs 55 by the nuts 56. The heaters may be placed in proper position merely by pushing them toward the rolls 10 whereby the latter will contact with the small rollers 26. The heaters may be pulled away from the rolls against the frictional connections referred to. In case of the breakage of a roll, the heaters are adapted to be moved away from the rolls by the broken pieces thereof against the frictional connections referred to thus preventing damage to the heaters. It will be apparent that the heaters readily may be removed from the mill merely by lifting them to remove the ears 57 from the bolts 58, while the arms 51 and 54 may be removed by lifting the former to slide the bolts 52 upwardly from the sockets 50. The outwardly flared lower ends of the outer walls of the heaters serve to protect the burner supply means to prevent injury to these elements due to sheets or other articles dropping in proximity thereto.

It is to be understood that the form of the invention herewith shown and described is to be taken as a preferred example of the same and that various changes in the shape, size and arrangement of parts may be resorted to without departing from the spirit of the invention or the scope of the subjoined claims.

50 I claim:

1. A roll heater comprising a casing including inner and outer walls and a central wall dividing the casing into inner and outer chambers communicating at their upper ends, the lower ends of said chambers being open, and a heating element arranged in the open end of said inner chamber.

2. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, and a heating

element arranged in the open end of said inner chamber.

3. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, and a burner pipe extending through the open end of said inner chamber parallel to said inner wall, said pipe being provided in its upper portion with a plurality of burner openings.

4. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, and a pair of concentric spaced pipes extending through the open end of said inner chamber parallel to said inner wall, the inner pipe being provided in its bottom portion with a plurality of outlet openings, the outer pipe being provided in its upper portion with a plurality of burner openings, said inner pipe being connected to a source of fuel supply.

5. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, a pair of concentric spaced pipes extending through the open end of said inner chamber parallel to said inner wall, the inner pipe being provided in its bottom portion with a plurality of outlet openings, the outer pipe being provided in its upper portion with a plurality of burner openings, and means for supplying a mixture of gas and air to said inner pipe.

6. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, a pair of concentric spaced pipes extending through the open end of said inner chamber parallel to said inner wall, the inner pipe being provided in its bottom portion with a plurality of outlet openings, the outer pipe being provided in its upper portion with a plurality of burner openings, a pair of caps engaging and covering the ends of said pipes, one of said caps being provided with a conduit communicating with said inner pipe, and means for

supplying a mixture of gas and air to said inner pipe.

7. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent the roll, a pair of concentric spaced pipes extending through the open end of said inner chamber parallel to said inner wall, the inner pipe being provided in its bottom portion with a plurality of outlet openings, the outer pipe being provided in its upper portion with a plurality of burner openings, a pair of caps engaging and covering the ends of said pipes, one of said caps being relatively long and provided with a transversely extending conduit communicating with said inner pipe, said last named cap being provided with a space communicating with the space between said pipes and provided with burner openings arranged in the top portion thereof, and means for supplying a mixture of gas and air to said conduit.

8. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent a roll, a heating element arranged in the open end of said inner chamber, and means for supporting said heater for movement toward and away from the roll.

9. A roll heater comprising a casing including inner and outer walls and a central wall dividing the casing into inner and outer chambers communicating at their upper ends, the lower ends of said chambers being open, said inner wall being curved to conform to the curvature of and adapted to be arranged adjacent a roll, a heating element arranged in the open end of said inner chamber, and a pair of arms arranged adjacent each end of said casing and pivotally connected to each other, one end of one arm of each pair being pivotally supported, the free end of the other arm of each pair being pivotally connected to said casing.

10. The combination with a rolling mill including a pair of rolls and journal hous-

ings therefor, supporting members carried by said housings, a pair of arms pivotally connected at one end to said supporting members, a pair of arms pivotally connected at one end to the opposite ends of said first named arms, means opposing turning movement between said arms, and a roll heater carried by said last named arm and adapted to be arranged in proximity to one of the rolls.

11. The combination with a rolling mill including a pair of rolls and journal housings therefor, of a roll heater supported by said housings adjacent one of said rolls, and a freely rotatable roller carried by the upper portion of said heater and projecting thereabove.

12. A roll heater comprising a casing including a pair of chambers communicating at their upper ends and having their lower ends open, one of said chambers being provided with a wall arranged adjacent the roll, and a heating element arranged in the lower end of said last mentioned chamber, the lower end of the other chamber being arranged a substantial distance above the lower end of said first mentioned chamber.

13. A roll heater comprising a casing including a chamber having an open lower end and including an inner wall arranged adjacent the roll and curved to conform to the curvature thereof, and a downwardly extending stack communicating at its upper end with the upper end of said chamber and having its lower end open and arranged a substantial distance above the open lower end of said chamber.

14. A roll heater comprising a wall having a portion arranged adjacent and conforming in curvature to the roll, the remaining portion of said wall being turned downwardly and spaced from the first named portion thereof and having its lower end terminating a substantial distance above the lower end of the first mentioned portion, a partition wall arranged between the portions of said first named wall and spaced therefrom throughout its height, and a heating element arranged between said partition wall and the first named portion of said first named wall adjacent the lower ends thereof.

In testimony whereof I affix my signature,

HAROLD E. McCREERY.
